UNITED STATES PATENT OFFICE.

JAMES I. AYER, OF CAMBRIDGE, MASSACHUSETTS, ASSIGNOR TO SIMPLEX ELECTRIC HEATING COMPANY, OF CAMBRIDGE, MASSACHUSETTS, A CORPORATION OF MASSACHUSETTS.

AUTOMATIC ELECTRIC WATER-HEATER.

1,029,523.

Specification of Letters Patent. Patented June 11, 1912.

Application filed January 2, 1912. Serial No. 669,067.

To all whom it may concern:

Be it known that I, JAMES I. AYER, a citizen of the United States, and resident of Cambridge, county of Middlesex, and State 5 of Massachusetts, have invented an Improvement in Automatic Electric Water-Heaters, of which the following description, in connection with the accompanying drawings, is a specification, like letters on the 10 drawings representing like parts.

This invention relates to electric water heaters for household and other uses, of a type especially designed to enable the drawing at frequent intervals of small quantities 15 of hot water, the automatic regulation of the device being arranged to keep a suitable supply of hot water always ready for use with a minimum consumption of current energy for this purpose.

20 The invention consists in an electric heating element extending into the body of a water-containing vessel and having a thermostat or like circuit controlling device arranged to be operated by the thermal conditions 25 of the vessel and its contents for opening the heating circuit when the water has reached a predetermined temperature, and closing the same when its temperature falls below this point.

30 The water-containing vessel is preferably inclosed with an insulating jacket, so that radiation is reduced to a minimum, and thus only a very small current supply is required to make up for the slight heat losses 35 which occur through radiation and keep the water in the vessel hot.

The invention will be better understood from the following detailed description, taken in connection with the accompanying 40 drawings, and will be thereafter pointed out in the appended claims.

Referring to the drawings: The figure shown is a central vertical section through the device, certain of the parts being shown 45 in elevation.

The vessel 10 may be of any desired form in cross section and in the preferred ar-

rangement shown is adapted to stand upright. It has a removable base plate 11, and spaced apart from said plate a removable bottom plate 12 for the water containing chamber, this bottom plate being shown as in threaded engagement with the interior of the vessel, as seen at 13, and having standing therefrom a central tubular housing 14 extending up through the body of the vessel and closed at its upper end. An electric resistance element 15 of any suitable form is mounted within this housing, this element being shown as an ordinary 60 resistance wire or ribbon wound on a tubular sleeve 16 and embedded in enamel 17, or the like. One of the terminal conductors 18 connects directly with this resistance element, and the other conductor 19 is connected to the other end of said resistance element through a thermostat 20, shown with a condenser 21 connected in multiple therewith. The thermostat 20, which typifies any suitable circuit controlling device 70 operable by the thermal condition of the interior of the vessel, is shown as formed of two strips of metal having dissimilar expansion coefficients, so that when fixed together as a compound plate it will bend 75 under the influence of heat, and break the circuit connection from its outer end to a contact pin 22, which is in connection with the resistance element and with the condenser by a connection 23, the conductor 19, 80 having connection with the other end of this compound plate and with the condenser, as seen at 24.

The water inlet pipe 25 opens into the lower part of the containing vessel as seen 85 at 26, and is controlled by a suitable valve 27. The water delivery pipe 28 is shown as extending up to near the top of the containing vessel at 29, as an overflow pipe, the water delivery being controlled from the valve 27 in the inlet, so that the discharge pipe takes water from the top of the heater 90 and in operation, as the cold water expands on heating, the accumulation of pressure in

the vessel is avoided. The entire vessel is preferably covered with an insulating jacket 30, an external casing being usually fitted over this insulating jacket in practice as a protection therefor. The thermostat, being thus housed in the base of the vessel and in proximity to the heater and to the water contents, is adapted for adjustment so as to break the circuit whenever the water 10 reaches any particular desired temperature from the boiling point downward; as a convenient means for adjusting the point at which breaking of the circuit will take place, the contact pin 22 may be formed as 15 an adjusting screw threaded through a post 31, as shown.

While the association of the condenser with the thermostat control is advantageous and desirable, it will be understood that in 20 many cases a condenser is not necessary, the current supply often being such that a thermostat will operate satisfactorily, without a condenser for reducing the spark. The heat insulating jacket 30, by preventing the dissipation 25 of the heat through conduction and radiation, thus prevents waste of current energy and causes the amount of current used to approximate that theoretically required for delivering any particular quantity of 30 water heated to the predetermined temperature for which the thermostat control is set.

It is to be understood that while the device as shown is provided with only a single heater, it is quite practicable to provide a 35 series of heaters and a series of thermostats with or without condensers, where more heat and a larger hot water delivery is required, for which the necessary amount of current could not conveniently be controlled with a 40 single thermostat.

While in the particular embodiment of the invention shown, the several parts constructed as set forth, coöperate in an efficient and especially advantageous manner, it is to 45 be understood that various of the details 50 may be modified and the relative arrangements of parts changed without departing from the spirit of the invention. For example, the invention in its broader aspects is not limited to any special form of circuit 55 control, so long as it is effected by the thermal condition of the vessel and its contents, and the particular location of the thermostat or the thermostat and condenser in the base and with the base formed as shown, is immaterial to the generic combinations which I desire to protect. I therefore do not 60 desire to be limited in these particulars, or in any others, except as set forth in the appended claims.

Having described my invention, what I claim as new and desire to secure by Letters Patent is:

1. A device of the kind described, comprising a vessel having liquid supply and

delivery connections, means for dividing off a portion of said vessel to form a lower base portion and an upper liquid holding body portion, an electric heater mounted in said body portion, and a thermostat in said base portion, said thermostat being formed and connected to render said heater inoperative at a predetermined thermal condition of the vessel contents.

2. A device of the kind described, comprising a vessel having liquid supply and delivery connections and formed with a removable bottom, a removable plate adapted to be fitted within said vessel to divide off the lower from the upper part thereof, an electric heater fitted within said vessel, and a thermostat mounted in said lower part of said vessel connected to control said heater by the thermal condition of the interior of the vessel.

3. A device of the kind described, comprising a vessel having liquid supply and delivery connections, one end thereof being removable, a removable partition dividing off said vessel to form a liquid holding body portion and an end portion separated therefrom, an electric heater mounted in said body portion of the vessel, and current controlling means mounted in said end portion of the vessel connected to control said heater and operable by the thermal condition of the vessel contents.

4. A device of the kind described, comprising a vessel having liquid supply and delivery connections, a removable plate fitted in said vessel for dividing off the same to form a liquid holding body portion and an end portion separated therefrom, said plate carrying a housing projecting into the body portion of the vessel, an electric heater fitted in said housing, and current controlling means for said heater mounted in said end portion of the vessel, said means being operable by the thermal condition of the vessel contents.

5. A device of the kind described, comprising a vessel having liquid supply and delivery connections, means for dividing off said vessel to form a liquid holding body portion and a base portion with a housing extending into the body portion, an electric heater fitted in said housing, and a thermostat with a condenser connected thereto mounted in said base portion, said thermostat being arranged and connected to control said heater and being operable by the thermal condition of the vessel contents.

6. A device of the kind described, comprising an inclosed vessel, means for dividing said vessel to form a lower base portion and an upper liquid holding body portion, a valve controlled inlet to the lower part of said body portion, an outlet connection from the upper part of said body portion, a housing extending into said body portion, an

electric heater in said housing, and a thermostat with a condenser attachment in said base, said thermostat being connected to open the circuit to said heater, as the vessel
5 and its contents reach a predetermined temperature.

In testimony whereof, I have signed my

name to this specification, in the presence of two subscribing witnesses.

JAS. I. AYER.
